UNITED STATES PATENT OFFICE.

WILLIAM L. GARRELS, OF ST. LOUIS, MISSOURI.

VALVE-GEAR.

SPECIFICATION forming part of Letters Patent No. 665,085, dated January 1, 1901.

Application filed July 24, 1899. Renewed October 24, 1900. Serial No. 34,179. (No model.)

To all whom it may concern:

Be it known that I, WILLIAM L. GARRELS, a citizen of the United States, and a resident of the city of St. Louis, in the State of Missouri, have invented certain new and useful Improvements in Valve-Gears, of which the following is a specification.

My invention relates to valve-gears, and has for its principal object to obtain constant lead and to cause preadmission, cut-off, release, and compression to occur at substantially corresponding points of the stroke.

To these ends my invention consists in the arrangements and combinations of parts hereinafter described and claimed.

In the accompanying drawings, which form part of this specification, and wherein like symbols refer to like parts wherever they occur, Figure I is a side elevation of my valve-gear, showing the parts on the near side in full lines, while the parts on the opposite side are shown in dotted lines. Fig. II is a plan view of my gear. Figs. III and IV represent a modification, being, respectively, a side elevation and a plan view of the connections of one valve only. Fig. V is a similar view to Fig. II with the parts somewhat differently arranged, and Fig. VI is a detail view of a modification of the devices which contribute the variable component of the valve motion.

My gear is arranged for use in connection with two separate engines or an engine having a plurality of cylinders. The valve for each cylinder or engine is connected to the reciprocating parts of both engines in such a way that the motion of each valve is substantially symmetrical with respect to the motion of the piston of its engine—that is, the curve whose coördinates represent corresponding positions of the valve and the piston approximates an ellipse. The connections of one valve are similar to those of the other valve, although there are certain obvious differences in detail arising from different locations of the parts. For convenience of reference the parts on one side of the engine are designated in the drawings by capital letters, whereas the corresponding parts on the other side are designated by the corresponding small letters.

The valve A is connected by a rod B to a lever C, and this lever is connected by a rod

D to a lever E, and this lever E is connected in turn by a rod F to the cross-head G of the same engine to which the valve A belongs. 55 The movement of the cross-head thus communicates a definite reciprocating motion to the valve of its engine, which motion is predetermined by the arrangement of the intermediate connecting devices, so as to overcome the lap and lead of the valve. The characteristic of the motion of the cross-head is that it is rapid in the middle of its stroke and slow at the end of its stroke. By the construction just described this characteristic motion is 65 transmitted to the valve, so that the opening and closing thereof are effected with a quick movement. Instead of having a fixed fulcrum, however, the lever C has a movable fulcrum—that is, it is a “floating” lever. 70 This movable fulcrum is a pivot H, by which it is connected to a rod I. This rod I carries a pivot-pin or a block K, pivotally fastened thereto, and this pin or block fits and slides on a curved link L, the curve of which is a 75 circular arc of a radius equal to the distance between the pivot-point H and the pivot pin or block K. The parts are so arranged that when the link L is in its middle position the pivot-point H coincides with the center of 80 curvature of said link. The middle point of the travel of the pivot or fulcrum H is thus fixed for all positions of the radius-rod I so long as the link L remains in its middle position—that is, in this position of said link the 85 pivot pin or block K may be shifted to any desired position on the link without changing said point.

The link L is fixed on a transverse rock-shaft m, which is connected to and rocked or 90 oscillated by the opposite engine. A convenient means for rocking such shaft is to have the lever e fixed thereto, as shown in the drawings. When the block K is concentric with the rock-shaft m, the block merely rocks 95 on its pivot, which remains stationary; but when the block K is shifted along the link to a position eccentric to the rock-shaft m said block receives a motion of translation, which is communicated through the radius-rod I to the combination-lever C. The extent of this motion depends on the distance of the block K from the center of the rock-shaft, and the direction of the motion imparted to the com-

bination-lever varies, according as the block is on one side or the other of said rock-shaft.

For the purpose of controlling the position of the block on the link the rod I has an elongated slot N, in which fits a pin O. This pin O is carried by an arm P of the tumbling-shaft Q, which is adapted to be manipulated by any suitable devices. The shaft Q is common to the two engines and carries two arms P and p, (one for each engine,) the arms being at an angular distance of about one hundred and eighty degrees apart. When the tumbling-shaft is turned, its crank-arms move the rods I i with it, whereby the blocks are slid along their respective links to any desired position thereon. When the tumbling-shaft Q is stationary in any position, the arms P p each fit in the slots of the respective radius-rods I i and act as fixed guides for said rods while they are being reciprocated by the rock-shafts. The pin or block K is thus forced to move in a substantially straight line, and the movement of the fulcrum H in one direction from the middle position is made substantially equal to the movement in the opposite direction. The motion at the pivot-point H of the combination-lever C is thus substantially symmetrical—that is, said pivot-point or fulcrum moves substantially equal distances to each side of its middle position.

From the foregoing description it is apparent that the valve motion is the resultant of two components, the first being a constant component derived from the reciprocating parts of its own engine and designed to give the proper lap-and-lead motion of the valves, and the second component being a variable motion derived from the other engine and designed to regulate the throw of the valve, and thereby vary the point of cut-off. Both of these components are substantially symmetrical motions and their resultant gives a substantially symmetrical motion to the valve. The motion of the valve is alternately swift and slow by reason of its being derived from the cross-heads, as hereinbefore explained. This alternation of quick and slow valve movement affords a rapid opening and closing of the valve.

In the modification illustrated in Figs. III and IV the parts and connections which furnish the lap-and-lead motion are the same as above described—that is, the valve A receives the constant component of its motion from the cross-head of its own engine through a rod F, connecting the cross-head G to a lever E, which is connected to another rod D, connected to a lever C, which is connected to the valve-rod B. As in Figs. I and II, the lever C is a floating lever whose fulcrum H at the middle position of the link L coincides with the center of curvature of the said link L, mounted on the rock-shaft m, extending from the other engine. A rod I is pivotally fastened to the floating lever and constitutes or carries the fulcrum H thereof. This rod I also carries a block K', which fits and slides

on said curved link or in a curved slot therein, and either a pin or a block K' or an extension thereof fits in an elongated slot R in a rod S. This rod S is pivoted at some fixed point X in the line, which passes through the centers of the rock-shafts M m, Fig. III, and the point of middle position of the fulcrum H on the valve side of the curved link. The other end of said rod S is connected by a link T to an arm U of the tumbling-shaft Q. The motion imparted to the block or pin K by the rock-shaft is thus restricted to a straight line, which makes the movement of the fulcrum symmetrical.

Fig. V is intended to illustrate the convenience with which my invention can be adjusted to various conditions in practice. The same parts are used as in Figs. I and II in modified forms and are designated by the same letters. The difference is that the rods I i pass through the holes made therefor in the rock-shafts M m. These spaces are provided for by enlarging the shafts at the points V and forming holes in such enlarged parts or by inserting cranks in said shafts. This view illustrates my gear as applied to parallel cylinders arranged close together with their valves between them.

The modification illustrated in Fig. VI is designed as a substitute for the parts which transmit the variable component of the valve motion from the rock-shaft to the combination-lever. In this modification the rod I², which carries the fulcrum H² of the combination-lever at one end, carries an eccentric-strap W at its other end. The form of the slotted link or block L² at the end of the transverse shaft m² is changed to have a circular contour over which the eccentric-strap W fits. The slotted link or block L² is not fixed on the shaft m², but moves with the eccentric-strap in the direction transverse to the rod I², and any suitable devices may be used for shifting the position of the eccentric strap or link L². The eccentric-rod may be guided by either of the methods hereinbefore described.

It is obvious that numerous changes and modifications may be made in the mechanical elements which go to make up the various connections and actuating devices, and I do not wish to restrict myself to such details of construction so long as the radius-rod pin in the slotted link or the equivalent of said pin is made to reciprocate in a practically straight line. Thus while the foregoing description mentions the reciprocating cross-heads as a source of movement, it is obvious that the connections might be made to other reciprocating parts or to the shaft.

What I claim is—

1. A valve-gear comprising a floating lever connected to a valve and connected through intermediate connecting devices to a moving part of the engine, a rod constituting the fulcrum of said lever, a curved link operatively connected to said rod and to a moving part

of the engine for imparting a reciprocating motion to the rod, and means for guiding said rod so that its point of connection to the link moves in a substantially straight line, substantially as described.

5. 2. A valve-gear for a plurality of cylinders comprising a floating lever connected to a valve and connected through intermediate connecting devices to a cross-head, a rod constituting the fulcrum of said lever, a rock-shaft connected by suitable connecting devices to another cross-head, a curved link on said rock-shaft, said rod and link being operatively connected to said rock-shaft and means for guiding said rod so that at its point of connection to said shaft it moves in a substantially straight line, substantially as described.

3. A valve-gear for a plurality of cylinders comprising a floating lever connected to a valve and connected through intermediate connecting devices to a cross-head, a rod constituting a fulcrum of said lever, a rock-shaft connected by suitable connecting devices to another cross-head, a curved link on said shaft, said rod operatively connected to said link and means for guiding said rod so that at such point of connection it moves in a substantially straight line, substantially as described.

30 4. A valve-gear for a plurality of cylinders comprising a floating lever connected to a valve and connected through intermediate connecting devices to a cross-head, a rod constituting a fulcrum of said lever, a rock-shaft connected by suitable connecting devices to another cross-head, a curved link operatively connected to said rod and said rock-shaft for imparting a reciprocating motion to said rod, a guide-pin for said rod and straight guides for said guide-pin, and a tumbling-shaft having a crank-arm adapted to shift said pin and guides simultaneously with the shifting of the connection of said curved link, substantially as described.

45 5. A valve-gear for a plurality of cylinders comprising a floating lever connected to a valve and connected through intermediate connecting devices to a cross-head, a rod constituting a fulcrum of said lever, a rock-shaft connected by suitable connecting devices to another cross-head, a curved link on said shaft operatively connected to said rod, and a tumbling-shaft having a crank-arm engaging in an elongated slot in said rod, substantially as described.

55 6. A valve-gear for a plurality of cylinders comprising a floating lever connected to a valve and connected through intermediate

connecting devices to a cross-head, a rod constituting the fulcrum of said lever, a rock-shaft connected by suitable connecting devices to another cross-head, a curved link operatively connected to said rod and said rock-shaft for imparting a reciprocating motion to said rod, a second rod pivoted in the line of middle position of said first-mentioned rod and having straight guides adapted to cooperate with the connection of said first-mentioned rod and shaft with said link, substantially as described.

7. A valve-gear comprising a floating lever connected to a valve and connected through intermediate connecting devices to the reciprocating parts of an engine, a rock-shaft operatively connected to other reciprocating parts, a curved link on said shaft, a rod constituting the fulcrum of said floating lever and connected by a slide to said link, the center of curvature of the curve of said link, at the middle position of said link coinciding with said fulcrum, and means for guiding said pin in a straight line, substantially as described.

8. A valve-gear comprising two reciprocating cross-heads, two rock-shafts having a lever fastened thereto and connected to the corresponding cross-head and said rock-shafts each having a link at its end, two floating levers each connected to a separate valve and each connected to the corresponding rock-shaft lever, two rods each constituting the fulcrum of the corresponding floating lever and having a pin fitting in the link on the rock-shaft operated by the opposite cross-head, and a tumbling-shaft having two oppositely arranged crank-arms, each of said crank-arms engaging a straight slot in the corresponding rod, substantially as described.

9. A valve-gear for two parallel engines, comprising two parallel rock-shafts operatively connected to different engines and each carrying a curved link, each link having a rod operatively connected thereto and constituting a fulcrum for a floating lever which is connected to the valve of one of the engines, each floating lever being connected to a moving part of the engine opposite that to which the corresponding rock-shaft is connected, said rock-shafts being formed with elongated openings and each rod extending through the opening in the rock-shaft which actuates the other rod to a reversing device common to both, substantially as described.

W. L. GARRELS.
